UNITED STATES PATENT OFFICE

171,714

CLOCK CASE

Samuel J. Kaufman, New York, N. Y., assignor
to Semca Clock Co., Inc., New York, N. Y.

Application November 6, 1952, Serial No. 22,153

Term of patent 7 years

(Cl. D42—7)

To all whom it may concern:

Be it known that I, Samuel J. Kaufman, a citizen of the United States, residing at New York city, in the county and State of New York, have invented a new, original, and ornamental Design for a Clock Case, of which the following is a specification, reference being had to the accompanying drawing, forming a part thereof.

Fig. 1 is a front view of a clock case, showing my new design.

Fig. 2 is a side view thereof.

I claim:

The ornamental design for a clock case, substantially as shown.

SAMUEL J. KAUFMAN.
